(57) CLAIM

The ornamental design for a laced handle holder, as is shown and described herein.

DESCRIPTION

FIG. 1 is a perspective view thereof;

FIG. 2 is a top elevational view thereof;

FIG. 3 is a right side elevational view thereof;

FIG. 4 is a bottom elevational view thereof;

FIG. 5 is a front elevational view thereof; and,

FIG. 6 is a rear plan view thereof.

The laced handle holder is shown with a symbolic break in its length. The appearance of any portion of the article between the break lines forms no part of the claimed design.
